UNITED STATES PATENT OFFICE.

WILLIAM H. SHANLEY, OF CHICAGO, ILLINOIS, ASSIGNOR TO THE PITKIN & BROOKS, OF SAME PLACE.

DESIGN FOR A GLASS VESSEL OR SIMILAR ARTICLE.

SPECIFICATION forming part of Design No. 32,948, dated July 17, 1900.

Application filed November 24, 1899. Serial No. 738,231. Term of patent 7 years.

To all whom it may concern:

Be it known that I, WILLIAM H. SHANLEY, a citizen of the United States, residing at Chicago, in the county of Cook and State of Illinois, have invented and produced a new and original Design for a Glass Vessel or Similar Article, of which the following is a specification, reference being had to the accompanying drawings, forming part thereof.

- Figure 1 is a plan view of a bottom of a dish with my new design thereon. Fig. 2 is a sectional view through center of dish shown in Fig. 1.

The design consists in the ornamentation, as herein described.

The leading or material features of my design consist of the figures *a*, *b*, and *c*, worked into the surface of the vessel or similar article. The figure *a* is distinguished by the tangential rays *a'* *a''*, surrounding the central portion *a³*. The central portion *a³* is

provided around its periphery with facets *a⁴* *a⁴* and has on its surface any geometrical figures, as *a⁶*. The figure *b* is adjacent to figure *a* and is composed of two pointed oblong members *b'* *b''*, crossing or intersecting each other at an angle, while the figure *c* is a fancy star formed from geometrical figures and is adjacent to both figures *a* and *b*.

Having described my invention, what I claim as new, and desire to secure by Letters Patent, is—

The design for a glass vessel or similar article substantially as shown and described.

In witness whereof I have hereunto subscribed my name in the presence of two witnesses.

WILLIAM H. SHANLEY.

Witnesses:

RALPH E. SMITH,
FRANK L. PITKIN.
